LIGHTNING-ARRESTER.

1,175,452.

Specification of Letters Patent. Patented Mar. 14, 1916.

Application filed February 21, 1911. Serial No. 609,944.

To all whom it may concern:

Be it known that I, RAY P. JACKSON, a citizen of the United States, and a resident of Edgewood Park, in the county of Allegheny and State of Pennsylvania, have invented a new and useful Improvement in Lightning-Arresters, of which the following is a specification.

My invention relates to lightning arresters and similar devices of the electrolytic cell type, and it has for its object to provide a device of this character which shall be simple, rugged and durable in construction and shall be particularly adapted to withstand rough usage and severe operating conditions.

The distinctive features of my present invention reside in a method of supporting the trays from their edges, a means for securing the trays rigidly together to form a single self-contained unit and a means for alining and assembling any desired number of such units one above the other in a compact structure.

Heretofore in this type of apparatus the trays have been spaced apart by insulating pieces in the form of washers, and the trays and washers have been held in place by means of wooden rods which projected through openings in the trays and in the washers. The rods have thus been in close proximity to the trays which has rendered the trays liable to short-circuit by reason of the absorption of moisture from the oil. Furthermore, it has been costly and inconvenient to assemble units of the former type and also to replace an insulating washer in case of breakage.

According to my invention, these difficulties are overcome, as the clamping tie-rods are entirely independent of the spacers and the trays. Moreover, the trays are carefully and safely spaced from the wooden supporting structure by means of the upper and lower clamping plates whereby all possibility of short-circuiting the trays is precluded.

My invention is illustrated in the accompanying drawings, in which—

Figure 1 is a view, partially in side elevation and partially in section, of a device constructed in accordance with my invention, and Fig. 2 is a partial plan view of the device shown in Fig. 1, certain portions being broken away and removed for the sake of clearness.

Referring to the drawing in detail, a tank 1 contains a supporting frame or standard 2 upon which a plurality of individual cell sections 3 and 4 are assembled, said sections comprising a plurality of fluid-containing trays 5 which are fitted one within another in a manner to be hereinafter set forth.

The supporting frame or standard 2 comprises a base portion 6, which rests upon the bottom 7 of the tank 1, upwardly projecting guide members 8 of insulating material and brackets 9 which constitute integral parts of the base portion 6.

The cell sections 3 and 4 are of similar structure and each comprises an upper clamping plate 10 and a lower clamping plate 11, between which are assembled a plurality of fluid-containing trays 5 which are supported and insulated from each other at their outer edges 12 by means of suitable insulating and spacing members 13. The upper and lower clamping plates 10 and 11 are severally provided with projecting lugs 14 which are secured to tie-rods 15 in order to clamp the component parts rigidly together to form a rigid and self-contained unit. The tie-rods 15 are spaced from and entirely independent of the trays 5 and spacers 13.

Each of the bottom clamping plates 11 is provided with downwardly projecting lugs or feet 16 which are disposed at the respective sides of the guide members 8 and are adapted to support the cell section and maintain it in position and alinement. The upper clamping plate 10 is provided with laterally projecting lugs 17 which span the

guide members 8 for alining and guiding purposes. The lower clamping plate 11 is annular in form and is adapted to receive the bottom tray 5 of the set and to make 5 intimate contact therewith, while the upper clamping plate 10 also constitutes an annular member which is provided with a downwardly projecting portion 18 the outer edge of which is inclined to conform to the general 10 shape of the outer portion 19 of the upper tray 5, so as to make intimate contact with its inner face.

The trays 5, which are adapted to contain a suitable electrolyte, are of like construction and are preferably made of aluminum, although other material may be employed. Each tray is provided with a centrally disposed frusto-conical indentation 21, which projects upwardly to a height slightly in 20 excess of that of the outer edge 12, and each indentation is provided with a relatively large central opening 22. In assembling the trays, the central openings 22 register to form a passage 23, through which circulation 25 of insulating liquid may be established in order to cool the several trays and maintain the apparatus in good operating condition. Inasmuch as the upper portions of the indentations 21 are of greater height than 30 the outer edges 12 of the several trays, the central openings 22 will have no tendency to drain the electrolyte with which the trays are filled.

The lower clamping plate 11 of the bottom 35 cell section 4 rests upon the base portion 6 of the supporting frame 2, which, in turn, rests upon the bottom of the containing tank 7, so that an electrical connection is established between the lowermost tray 40 and the containing tank. A contact bridge 24 is provided above the upper clamping plate 10 of the uppermost cell section 3 and it is maintained in position by means of lugs 25 which are disposed at the respective sides 45 of the guide members 8. The ends of the contact bridge 24 rest upon the upper clamping plate 10 and are held in intimate contact therewith by means of set screws 26 which coöperate with the clamping plate 10 50 to rigidly secure the bridge 24 thereto. A terminal member 27 is secured to the middle portion 28 of the bridge 24 and thus an electrical connection is established between said terminal member and the upper tray 5 of the 55 upper cell section 3.

The completion of the electrical circuit between the cell sections 3 and 4 is accomplished through the feet 16 of the lower clamping plate 11 of the upper section 3, 60 which support said section upon the projecting lugs 17 of the lower adjacent clamping plate 10 of the cell section 4.

Those skilled in the art will readily un-

derstand that, inasmuch as each cell section constitutes a complete and self-contained unit, a lightning arrester adapted for any desired voltage may be constructed by assembling a sufficient number of cell sections, one above another, in the manner hereinbefore set forth.

In preparing the lightning arrester for service, the component parts are assembled as hereinbefore shown and described, after which the several trays are filled with a suitable electrolyte according to the usual practice. The whole structure is then immersed in a suitable insulating oil which is contained within the tank 1 and is adapted to suppress discharges between the several trays and to cool and maintain the structure 80 at a substantially uniform temperature. Inasmuch as the specific gravity of the insulating oil is less than that of the electrolyte, there is no tendency for the electrolyte to be disturbed or displaced thereby.

In operation, when the oil has become heated, it slowly rises through the central passage 23, and a liberal circulation thereof is established which dissipates the heat by distributing it throughout the whole structure.

It will, of course, be understood that, although I have shown and described a device of specific structural detail, many modifications may be effected therein without exceeding the spirit and scope of my invention, and I desire that only such limitations shall be imposed as are indicated in the appended claims.

I claim as my invention:

1. In an electrolytic lightning arrester, the combination with a liquid-containing tank and a supporting frame disposed therein and having upwardly projecting guide members, of a plurality of self-contained cell sections disposed one above another and held in position by said guide members, each cell section embodying suitable means for coöperating with said guide members.

2. In an electrolytic lightning arrester, the combination with a liquid-containing tank and a supporting frame disposed therein and having upwardly projecting guide members, of a plurality of independent cell structures resting one upon another and maintained in position by said guide members, each cell structure comprising a plurality of trays, spacing members for supporting said trays at the edges thereof, clamping plates disposed in intimate contact with the upper and lower trays, and means for securing said plates together.

3. In an electrolytic lightning arrester, the combination with a liquid-containing tank and a supporting frame disposed therein and having upwardly projecting guide

members, of a cell structure comprising a plurality of trays fitted one within another, insulating members disposed between the edges of adjacent trays, clamping members disposed in intimate contact with the upper and lower trays and provided with projecting members to engage said guide members, and suitable tie-rods for securing said plates rigidly together.

4. In an electrolytic lightning arrester, the combination with a liquid-containing tank and a supporting structure therein, of a plurality of spaced trays nested one within another, clamping plates disposed in con-

tact with the upper and lower trays and having oppositely projecting lugs, and tie-rods independent of said trays for engaging said lugs, said clamping plates also being provided with bifurcated lugs for engaging said supporting structure and spacing said trays therefrom.

In testimony whereof, I have hereunto subscribed my name this 17th day of Feb., 1911.

RAY P. JACKSON.
